DRY SHAVER

Michele Grivetto, Turin, Italy; vested in the
Allen Property CustodianApplication August 29, 1939, Serial No. 292,479
In Italy September 3, 1938

12 Claims.

(Cl. 30—43)

This invention relates to dry shavers of the type comprising a movable blade which performs very rapid angular oscillations and a stationary blade obtained on or forming part of the cylindrical casing of the movable blade.

An object of this invention is to provide a dry shaver of the above-mentioned type, in which the stationary blade is constituted by one side of a longitudinal substantially continuous slot in the cylindrical casing, which is further provided with a bearing surface for the skin, the plane of said surface being substantially tangential to the arc of circle described by the cutting edge of the movable blade and normal to the plane passing through the axis of oscillation of the movable blade and the cutting edge of the stationary blade. With this arrangement the hair is cut at its root, that is, quite near to the skin, without hurting the latter.

A further object of the invention is to provide a dry shaver of the above-mentioned type, in which cuts normal to the cutting edge of the stationary blades are provided in the bearing surface for the skin on the side opposite to the stationary blade to form guides for the hair.

Another object of the invention is to provide in a dry shaver of the above-mentioned type narrow bridges arranged transversely to the slot and connecting the cutting edge of the stationary blade to the portion of the bearing plane opposite to said cutting edge. These bridges are adapted to stiffen the stationary blade and obtain a continuous bearing plane for the skin; they moreover show the advantage that the hair is not bent between the bearing plane and the skin and is prevented from being brought between said parts, thus holding the cutting edge of the stationary blade at a distance from the skin; the hair is thus cut at its root.

These and other advantages will appear from the following specification with reference to the annexed drawing, in which:

Figure 1 is a longitudinal section of the shaver head;

Fig. 2 is a section on line II—II of Fig. 1;

Fig. 3 is a section on line III—III of Fig. 1;

Fig. 4 is a partial section on line IV—IV of Fig. 2;

Fig. 5 is a front view of the movable blade;

Fig. 5a is a sectional view thereof;

Fig. 6 is a partial cross section of the shaver head showing a modified form;

Fig. 7 is a side partial view of Fig. 6 seen in the direction of the arrow VII;

Fig. 8 is a view similar to Fig. 6 of a further modified construction, and

Fig. 9 is a partial side view of Fig. 8 seen in the direction of the arrow IX.

5 Referring to Figures 1 to 5, 1 denotes the semi-cylindrical casing receiving the movable blade 2, which oscillates about the geometrical axis 0 of the casing in the manner described hereinafter.

In the cylindrical wall of the casing 1 is a 10 milled cut 3 which extends over the whole length of the casing, except the regions in nearest proximity to its end portions. The bottom of the milled cut 3 forms a bearing surface 4 for the skin, on which the shaver is moved to and fro.

15 The bearing surface 4 is discontinuous owing to the slot 7 which forms the cutting edge 5 for the stationary blade. This cutting edge 5 is situated at the end of the radius 6 which is normal to the bearing surface 4. As the stationary blade 20 is necessarily of a certain thickness, its edge is tapered, in order to bring the cutting edge 5 as near as possible the cutting edge of the movable blade oscillating underneath the former.

The blade 2 is provided on the axis of oscillation 0 with two semicylindrical surfaces 11, seated in correspondingly shaped recesses in two pins 10. The latter are subjected to the action of springs 13, that push the free blade end against the edges 1a of the casing 1, insuring a perfect 30 articulation with a minimum friction for the blade oscillations.

The pins 10 and springs 13 are eccentrically mounted in cylinders 12, rotatable in seatings formed in a supporting base 19 fixedly connected 35 with the casing 1. The cylinders 12 are formed with lower grooves 12a which permit angular displacements of the cylinders 12, thereby transversely displacing the pins 10, in order to adjust the support of the blade 2. The cylinders 12 are 40 locked in their adjusted position by means of set screws 14. The blade 2 is formed at its lower end with a central projection 15, having a slot 16 receiving an eccentric pin 17 on a shaft 18. The shaft 18 is rotated by a motor (not shown) 45 suitably incorporated in the shaver, imparting to the blade 2 very rapid oscillatory movements.

The width of said oscillations is such that the cutting edge of the movable blade 2 does not move over the whole width of the slot 7, but only over a part thereof. In fact, the position of the blade 2, shown in Figure 2, approximately corresponds to the final blade position. The object of this arrangement is to facilitate admission of longer hair into the slot 7 and to set it upright for cutting. The grooves 8 (Figure 4) formed in the 55

portion of the bearing surface opposite the cutting edge 5, exert a combing action on the longer hair, assisting in setting it upright in the proper direction as it enters the slot 7. In order to facilitate the passage of this long hair in the region situated between the blade 2 and cutting edge 5, the blade 2 may also be provided with grooves 9 (Figure 5) which are, however, inclined in order to secure continuousness of the blade cut.

Referring to Figures 6 and 7:

The general construction corresponds to that shown in the formerly described construction, and details need not be repeated. The bearing surface 4 for the skin still is normal to the radius 6 passing through the edge of the stationary blade 5. The modification concerns only the portion 1' of the casing opposite the stationary blade. This portion is formed with cuts 20 instead of simply with grooves as provided in the constructions shown in Figs. 1 to 5, and extends towards the stationary blade 5, so that the width of the slot 21 is limited to about $5/10$ millimeter. The width of the extreme angular displacements of the oscillating blade 2 at its edge is greater and extends beyond the slot portions 21 at both sides thereof.

Figure 6 shows by way of example in dotted and full lines, respectively, the two final positions of the oscillating blade 2. It will be obvious that, in order to reach the position shown in full lines, the oscillating blade moves over a certain length of the zone of the member 1' formed with cuts 20.

The support 18 for the outer casing and cylinders 12 may be moulded from a plastic composition, for instance of the type known under the registered name of Bakelite, which makes construction less expensive.

In order to prevent cut hair from entering the mechanism for driving and adjusting the movable blade, the semicylindrical chamber in which the blade 2 oscillates, is closed towards this mechanism by a plate 22 having only holes for the passage of the tail 15 actuating the blade 2 and pins 16 supporting said blade.

Referring to Figs. 8 and 9, the portion 23 of the bearing surface for the skin, opposite to the cutting edge 24 of the stationary blade, is connected to the remaining part 25 of said bearing surface by means of a set of narrow bridges 26 formed by providing in the portion 1b of the casing deep cuts 27 perpendicularly to the stationary blade. The width of said bridges is about $3/10$ mm., while the cross cuts may be, for instance, of $7/10-13/10$ mm. width.

In order to cut the hair to the root, as the slot 28 in the construction now described is no longer continuous, the cutting edge of the blade is tapered, as shown in the drawing, with a large development of the tapered surface. This taper is economically formed by the same milling cutter used to form the cuts 27. The milling cutter is shown in dotted lines in Figure 8, where it is denoted by the letter F. By effect of the blade taper, the skin slightly enters the cuts 27 by effect of the pressure with which the shaver is applied to the skin, and brings the hair root against the movable blade 2, by which the hair is cut as the movable blade comes over the cutting edge 24 of the stationary blade.

The cuts 27 subdivide the hair, bringing it on the stationary blade, where they are cut by the movable blade, as stated above.

What I claim is:

1. A dry shaver comprising a semi-cylindrical casing, a blade mounted for oscillation in said cylindrical casing about the axis of the latter

and having a cutting edge movable substantially along an arc of the inner cylindrical surface of said casing, the outer portion of the semi-cylinder being cut away between the ends thereof along a plane extending substantially tangentially to the inner cylindrical surface thereof to provide a cutting edge at the intersection of said plane and the inner cylindrical surface, said semi-cylinder being further cut away to provide

10 a slot having the cutting edge as one of its edges, and means for imparting to said oscillating blade an oscillatory motion extending over a part only of the slot width.

2. A dry shaver comprising a semi-cylindrical casing, and a blade mounted for oscillation in said cylindrical casing about the axis of the latter and having a cutting edge movable substantially along an arc of the inner cylindrical surface of said casing, the outer portion of the semi-cylinder being cut away between the ends thereof along a plane extending substantially tangentially to the inner cylindrical surface thereof at a plurality of regions to provide a cutting edge at the intersection of said plane and the inner cylindrical surface, said semi-cylinder being further cut away to provide a plurality of slots extending from the cutting edge to receive hairs to be cut.

3. A dry shaver comprising a cylindrical casing, a blade in said casing mounted for oscillation about the axis of the latter, and a spring support in said casing for said blade tending to bring the cutting edge of said blade into engagement with the inner cylindrical surface of said casing, the outer portion of the semi-cylinder being cut away between the ends thereof along a plane extending substantially tangentially to the inner cylindrical surface thereof at a plurality of regions to provide a cutting edge at the intersection of said plane and the inner cylindrical surface, said semi-cylinder being further cut away to provide a plurality of slots extending from the cutting edge to receive hairs to be cut.

4. A dry shaver as claimed in claim 3, in which the free end of the movable blade is provided with oblique grooves adapted to comb the longer hair to facilitate their admission into the cutting zone.

5. A dry shaver comprising a cylindrical casing, a blade in said casing mounted for oscillation about the axis of the latter, a spring support in said casing for said blade tending to bring the cutting edge of said blade into engagement with the inner cylindrical surface of said casing, the outer portion of the semi-cylinder being cut away between the ends thereof along a plane extending substantially tangentially to the inner cylindrical surface thereof at a plurality of regions to provide a cutting edge at the intersection of said plane and the inner cylindrical surface, said semi-cylinder being further cut away to provide a plurality of slots extending from the cutting edge to receive hairs to be cut, and means for swinging the cutting edge of the movable blade to a distance not less than $5/10$ millimeters from the stationary cutting edge.

6. A dry shaver comprising a cylindrical casing having a longitudinal slot, one side of which constitutes the cutting stationary edge, a bearing plane for the skin formed on the outer face of said casing being substantially tangential to the cylindrical inner surface of said casing along a line coinciding with the cutting edge of said stationary blade, the portion of the bearing surface opposite to the stationary blade being provided with grooves normal to said stationary

blade and a blade mounted to oscillate in said casing and having its free end in engagement with said cylindrical inner surface and provided with grooves inclined to the direction of movement of said movable blade.

7. A dry shaver comprising a cylindrical casing having a narrow discontinuous longitudinal slot, one side of which constitutes the stationary blade, a plurality of narrow bridges through said slot, a bearing plane for the skin formed on the outer face of said casing being substantially tangential to the inner cylindrical surface of said casing along a line coinciding with the cutting edge of said stationary blade, the portion of the bearing surface opposite to the stationary blade being provided with a plurality of deep cuts between said bridges and a movable blade mounted to oscillate in said casing and having its cutting edge in engagement with said inner cylindrical surface.

8. A dry shaver comprising a cylindrical casing having a longitudinal slot, one side of which constitutes the cutting stationary edge, a bearing plane for the skin formed on the outer face of said casing being substantially tangential to the cylindrical inner surface of said casing along a line coinciding with said cutting edge and a blade mounted to oscillate in said casing and having its cutting edge in engagement with said inner cylindrical surface, an adjustable spring support in said casing for said movable blade tending to bring the cutting edge of said blade into engagement with the inner cylindrical surface of said casing and means for imparting to said movable blade an oscillatory motion extending over a part only of the slot width.

9. A dry shaver comprising a cylindrical casing, a movable blade in said casing mounted for oscillation about the axis of the latter, pins with a cylindrical bearing surface for supporting said movable blade, angularly adjustable cylinders having eccentric holes in which said pins are elastically supported, a base support carrying said cylinders and said casing, a cutting edge formed on one side of a longitudinal slot formed in said casing, a bearing plane for the skin formed on the outer face of said casing along a line coinciding with said cutting edge, said bear-

ing plane being normal to the plane passing through the axis of oscillation of the movable blade and the stationary cutting edge.

10. A dry shaver as claimed in claim 9, comprising further means for imparting to said movable blade an oscillating motion and a plate to protect said driving means and said adjustable cylinders against access of cut hair.

11. A dry shaver comprising a cylindrical casing having a longitudinal slot, one side of which constitutes the cutting stationary edge, a bearing plane for the skin formed on the outer face of said casing being substantially tangential to the cylindrical inner surface of said casing along a line coinciding with the cutting edge of said stationary blade, the portion of the bearing surface opposite to the stationary blade being provided with a plurality of deep cuts normal to said blade, a movable blade mounted to oscillate in said casing and having its cutting edge in engagement with said inner cylindrical surface, pins with a cylindrical bearing surface for supporting said movable blade, angularly adjustable cylinders having eccentric holes in which said pins are elastically supported and a base support carrying said cylinders and said casing.

12. A dry shaver comprising a cylindrical casing having a narrow discontinuous longitudinal slot, one side of which constitutes the stationary blade, a plurality of narrow bridges through said slot, a bearing plane for the skin formed on the outer face of said casing being substantially tangential to the inner cylindrical surface of said casing along a line coinciding with the cutting edge of said stationary blade, the portion of the bearing surface opposite to the stationary blade being provided with a plurality of deep cuts between said bridges and a movable blade mounted for oscillation in said casing and having its cutting edge in engagement with said inner cylindrical surface, pins with a cylindrical bearing surface for supporting said movable blade, angularly adjustable cylinders having eccentric holes in which said pins are elastically supported and a base support carrying said cylinders and said casing.

MICHELE GRIVETTO.
